SPRING SUPPORT DEVICE
Leonard S. Suozzo, Hackensack, N.J.
(50 Church St., New York 7, N.Y.)
Filed Mar. 29, 1962, Ser. No. 183,638
6 Claims. (Cl. 248—54)

This invention relates to the art of support devices and, more particularly, to a spring support device for properly and adequately supporting a load and for permitting movement of the load as required by particular conditions of use.

The spring support device of this invention is capable of effectively supporting various types of loads. The device is specially useful for supporting and maintaining wires, cables and the like under proper tension. In this connection, the device of the present invention may be advantageously employed in electrified railroads which utilize electrically conductive overhead trolley wires. Such wires are usually strung between spaced vertical columns or poles. The spans between pairs of successive columns or poles are frequently quite long. As a consequence, the length of wire in an individual span may expand or contract substantially due to variations in ambient temperature and use conditions. This results in corresponding variations in both the sag and the tension of the wire in a span. The sag of the wire may vary from a few inches to 24 inches, or more, and the tension may vary correspondingly.

The device of this invention may also be beneficially employed in other locations, including steam power plants and various categories of chemical plants, for adequately supporting piping arrangements while permitting substantial movement of the piping as the result of expansion or contraction thereof, due to temperature changes in the material of the piping.

The spring support device of this invention is capable of performing a number of desirable functions, depending on its specific intended use. Moreover, the device is very versatile and may be utilized to afford a variable supporting force, a constant supporting force or a combination variable-constant supporting force. The nature of the supporting force afforded by the device depends on the particular type of spring means employed and its relationship to other cooperating parts of the device, as will be evident to persons trained in the art from the detailed description that follows.

A principal object of this invention is to provide a spring support device having improved structural features and operational characteristics.

Another object of the invention is to provide a spring support device that is adapted to properly support a load and, at the same time, permit substantial travel of the load, as required by conditions of use.

A further object of the invention is to provide a spring support device that may have the attributes and characteristics of and serve as a variable support device, a constant support device, and/or a combined variable support device and constant support device, depending on the specific design employed and the relationship of the spring means to other parts of the device.

It is a still further object of the invention to provide a device of the character indicated that is simple, compact and lightweight in design; that is sturdy and durable

2

in construction; that is reasonable in manufacturing, installation and maintenance costs; and that is capable of performing its intended functions in a safe and dependable manner.

5 The enumerated objects and other objects, together with the advantages of the invention, will be readily understood by persons trained in the art from the following detailed description and the accompanying drawings which respectively describe and illustrate a complete spring support device of this invention and several modifications thereof.

In the drawings, wherein like reference characters denote corresponding parts throughout the several views:

15 FIG. 1 is an elevation view of a spring support device constructed in accordance with this invention, the device being suspended from an overload supporting structure and operatively connected to a load;

FIG. 2 is an enlarged view taken along line 2—2 of FIG. 1;

20 FIG. 3 is a view taken along line 3—3 of FIG. 2;

FIG. 4 illustrates the spring support device of FIGS. 1, 2 and 3 mounted on a vertical supporting structure instead of an overhead supporting structure;

25 FIG. 5 corresponds to FIG. 2 and illustrates a modified form of spring support device of this invention;

FIG. 6 corresponds to FIG. 3 and illustrates another modification of the invention;

30 FIG. 7 is an enlarged view of the cam and pulley arrangement shown in FIG. 6;

FIG. 8 is a spring characteristic diagram which is derived from the use of disc springs of the type shown in FIG. 3; and

35 FIG. 9 is a spring characteristic diagram which is derived from the use of a helical compression spring shown in FIG. 6.

40 Referring initially to FIGS. 1, 2 and 3, the therein illustrated spring support device of this invention is generally designated by the letter D. This form of the invention comprises a housing H which consists of a cylindrical side wall 10, a first end wall 11 which is welded to the side wall, as indicated at 12, and a second end wall 13 which is spaced from end wall 11 and is welded to the side wall, as indicated at 14. End wall 11 is provided with a central through opening 15 while end wall 45 13 is provided with a like but larger opening 16.

45 Positioned within the housing is a pair of rectilinear guide tubes 17 and 18 which are coaxial with each other and with openings 15 and 16. Guide tube 17 is welded to end wall 11, as indicated at 20, while guide tube 18 is welded to end wall 13, as indicated at 21. A tubular backing member 22, which is open at its right end, as viewed in FIG. 3, has a central opening 23 in its closed end. Member 22 is slidable in guide tube 17 and along guide tube 18. A tubular element 24 is coaxial with opening 23 and is welded to the closed end of member 22, as indicated at 25. Element 24 is formed with a pair of diametrically opposed slots 26.

50 A plurality of sets 27 of disc springs 28 is carried by guide tube 18. A spacing ring 30 is positioned between 55 each set of springs. Additionally, a spacing ring 31 is disposed between the free end of tubular member 22 and the next adjacent disc spring 28 and a like spacing ring 32 is located between housing end wall 13 and the next adjacent disc spring. The configuration and arrangement

of individual disc springs 28 and sets of such springs may be the same as or similar to those which are illustrated and described in my Patent No. 2,939,663, granted June 7, 1960, to which reference may be had for details of construction and operation.

Device D also comprises a pair of spaced parallel plates 34 which are positioned to opposite sides of the center of opening 16. Plates 34 are welded to end wall 13 and extend to the right of housing H, as viewed in FIGS. 1 and 3. A third plate 35 spans the space between plates 34 and is welded thereto, as indicated at 36. Plate 35 is provided with a plurality of openings for reception of bolts 37 whereby the device may be attached to an overhead beam or the like 38. Plates 34 are provided with aligned circular openings 40 and aligned arcuate slots 41. A portion of each plate, which defines a corresponding slot 41, is provided with a scale having graduations 42 to indicate load travel.

A stationary shaft 43 is secured at its ends to plates 34. A rotary member 44 is positioned between plates 34 and is rotatable about the axis of shaft 43. Member 44 is an incomplete circular pulley in that the arcuate portion of its periphery does not form a complete circle. It will be evident from an examination of FIG. 3 that member 44 is the equivalent of a sector of a circular pulley and has an arcuate peripheral groove 45 (FIG. 2). Member 44 carries a pin 46 which is parallel to shaft 43 and registers with plate slots 41. This pin serves as a stop element to limit angular movement of member 44 relative to plates 34 in opposite directions about the axis of shaft 43. Each end of pin 46 is formed with an indicator pointer 47 that cooperates with graduations 42 to denote load travel. Member 44 has at least one circular opening 48 that is adapted to be aligned with plate openings 40. A removable pin 49 registers with openings 40 and 48 and maintains member 44 in selected angular position relative to plates 34. This pin is mounted in place at the time the device is assembled and is removed after the device is installed and adjusted.

Affixed to member 44, preferably by welding, is a pair of guide members 50 and 51 which define parallel guide grooves 52 and 53, respectively, that are equi-spaced from the axis of shaft 43. A third guide member 55 is also welded to member 44 and is normal to guide grooves 52 and 53. This guide member carries a scale having graduations 56. A wedge type member 57 is slideable along member 55 and has an indicator marking 58 that coacts with graduations 56 to denote its position relative to member 55. An adjusting screw 60 extends through member 51 and engages a tap 61 in member 55.

A slide block 62 is cooperatively associated with guide members 50 and 51 and wedge member 57. Block 62 is generally U-shaped and defines an opening 63 for reception of shaft 43. This block has side extensions 64 and 65 that respectively register with guide grooves 52 and 53. The free ends of the block bear against the inclined face of the wedge member while the other end or web portion is formed with an arcuate groove 66. It will be appreciated from an examination of FIG. 3 that the distance from the axis of shaft 43 to groove 66 may be increased or decreased, as desired, by turning adjusting screw 60 whereby to correspondingly move wedge member 57 toward the left or toward the right.

A first flexible connector, such as a wire rope 67, is anchored at one end to a block 68. Integral with block 68 is a pair of coaxial pins 70 that register with slots 26 to permit axial movement of the block relative to tubular element 24 and prevent relative angular movement of these parts. Block 68 is equipped with a threaded rod 71 which extends through and beyond opening 23 in tubular member 22 and which is provided with an adjusting nut 72. The other end of the wire rope is anchored to side block 62, as indicated at 73, and rides in arcuate groove 66.

A second flexible connector, such as a wire rope 74, is

anchored at one end to member 44, as indicated at 75, and rides in its groove 45. The other end of wire rope 74 is connected to a load L, such as a piping section 76, by means of a strap 77 which embraces the piping section.

For the purpose of outlining the operation of the form of the invention shown in FIGS. 1, 2 and 3, it is assumed that device D has been assembled and is mounted, as illustrated in FIG. 1, with plate 35 connected to beam 38 and with wire rope 74 connected to piping load L. It is also assumed that the parts of the device are in the relative position shown in FIG. 3. In the course of installation, preset pin 49 is removed, thereby allowing the parts of the device to operate and function in a normal manner.

The force exerted by load L is transmitted through wire rope 74, member 44, member 62, wire rope 67, connector 71, and backing member 22 to disc springs 28. The springs are so constructed and arranged as to supply a variable supporting force, a constant supporting force or a combination variable-constant supporting force, depending on the selected range of deflection of individual springs. Also, members 62 and 44 are so constructed and arranged as to permit preselected travel of the load in response to corresponding deflection of individual disc springs. Such load travel may be varied by correspondingly moving wedge member 57. This is accomplished by turning adjusting screw 60 so that the distance from the axis of shaft 43 to groove 66 is increased or decreased, as desired, to meet particular load travel requirements.

FIG. 4 illustrates above-described device D secured to a vertical supporting structure, such as a building column 78. The arrangement shown in this view is similar to that in earlier views, the essential difference being that device D is turned 90° from the position shown in FIG. 1.

The modification of the invention shown in FIG. 5 differs over that appearing in FIGS. 1, 2 and 3 only in that it utilizes a pair of members 44 and a pair of wire ropes 74 instead of a single member 44 and a single wire rope 74. In FIG. 5, both members 44 are preferably coupled for rotation in unison about the axis of shaft 43.

Referring now to FIG. 6, the spring support device of the modification of the invention illustrated therein is generally denoted by the letter D'. This form of the invention embodies a number of parts and elements which were earlier described, including housing H, plates 34 and 35, tubular element 24, slide block 68, wire ropes 67 and 74 and stationary shaft 43.

In FIG. 6, a section of tubing 79, which may be the same as or similar to guide tube 18, is positioned in the housing and is welded to end wall 13. A guide pulley 80 is located within tubing section 79 and is mounted for rotation about the axis of a shaft 81 which is secured to the tubing section. Also positioned in the housing is a helical compression spring 82 which bears at one end against housing wall 13 and at its other end against a backing plate 83. Tubular element 24 is welded to the backing plate and threaded rod 71 of its slide block 68 extends through a central opening 84 in the backing plate.

A substantially complete circular pulley 85 is disposed between plates 34 and is rotatable about the axis of shaft 43. This pulley is provided with a peripheral groove 86 and carries a pin 46 (earlier described) which registers with elongated arcuate grooves 87 that correspond to grooves 41.

A cam 90 is secured to pulley 85 and is rotatable therewith about shaft 43. The cam has a peripheral groove 91. Wire rope 67 is anchored at one end to block 68, bears against guide pulley 80, rides in cam groove 91 and is secured at its other end to cam 90 by a connector 92.

Wire rope 74 is anchored at one end to pulley 85, as indicated at 93, and rides in pulley groove 86. The other end of this wire rope is adapted to be connected to a load in the same manner or a similar manner to that described with reference to FIG. 1.

The camming peripheral surface of cam 90 defines an involute type curve, as best shown in FIG. 7, wherein k =the spring constant of spring 82, i.e. the rate of change of spring force per inch; $F=k$ times the compression of spring 82 in inches; L =the load supported by the device; r, r_1, r_2, r_3 =successive radii extending from the axis of rotation of the cam to its camming surface; and R =the radius of pulley 85.

The parts are so designed and arranged that the moment of the spring force is equal to the moment of the load. This relationship may be expressed in the following equation:

$$Fr=LR$$

The values of F , L and R may be preselected, after which the value of r may be determined by the use of this equation. Thus,

$$r = \frac{LR}{F}$$

The values of r_1, r_2, r_3 , etc., may be similarly determined:

$$r_1 = \frac{LR}{(F+k)}$$

$$r_2 = \frac{LR}{(F+2k)}$$

$$r_3 = \frac{LR}{(F+3k)}$$

The operation of the form of the invention shown in FIG. 6 is similar to that of FIGS. 1, 2 and 3. It will be appreciated that the construction appearing in FIG. 6 permits the device to serve as a constant support.

The load-deflection curve shown in FIG. 8 is based on the use of disc springs. The flat portion of the curve, labelled a indicates the part of the deflection of the disc springs which affords constant support. The portions labelled b and b_1 indicate deflection ranges in which the force exerted by the disc springs is partly constant and partly variable. Thus the use of disc springs in the device of FIGS. 1, 2 and 3 permits the device to afford constant and/or variable support.

Referring to FIG. 9, it will be observed that the illustrated load-deflection curve is that of a helical spring, such as spring 82, and is a straight line. The force exerted by such a spring is variable. However, by utilizing the cam 90 and designing and arranging the parts as earlier described, the moment of the spring force is equal to the moment of the load, and the device is capable of functioning as a constant support.

From the foregoing, it is believed that the construction, operation, objects and advantages of my present invention will be readily comprehended by persons skilled in the art, without further description. It is to be clearly understood, however, that various changes in the construction described above and illustrated in the drawings may be made without departing from the scope of the invention, it being intended that all matter contained in the description or shown in the drawings shall be interpreted as illustrative only and not in a limiting sense.

I claim:

1. A device of the character described comprising support means including a housing having an end wall, a guide tube affixed to the end wall and projecting into the housing, a backing member within the housing, said backing member being spaced from and movable relative to the end wall, spring means within the housing, said spring means being positioned between and bearing against the end wall and the backing member, said spring means com-

prising at least one disc spring having a central opening through which the guide tube extends, said disc spring being slidable along the guide tube, a shaft carried by the support means and disposed to the side of the end wall remote from the spring means, a rotary member mounted for rotation about the axis of the shaft and having a peripheral portion which is a substantial part of an arc of a circle, a unit secured to and rotatable with the rotary member, said unit being slidable along a path that is substantially parallel to a radius of the rotary member and having a curved peripheral portion, a first flexible connector secured at one end to the backing member and at its other end to the unit, said flexible connector engaging said curved peripheral portion of the unit, and a second flexible connector secured at one end to the rotary member and adapted to be secured at its other end to a load, said second flexible connector engaging said portion of the rotary member.

2. A device of the character described comprising sup-

port means including a housing having an end wall, a guide tube affixed to the end wall and projecting into the housing, a backing member within the housing, said back- ing member being spaced from and movable relative to the end wall, spring means within the housing, said spring

means being positioned between and bearing against the end wall and the backing member, said spring means comprising at least one disc spring having a central opening through which the guide tube extends, said disc spring being slidable along the guide tube, a shaft carried by

30 the support means and disposed to the side of the end wall remote from the spring means, a rotary member mounted for rotation about the axis of the shaft and having a peripheral portion which is a substantial part of an arc of a circle, a unit secured to and rotatable with

35 the rotary member, said unit having a curved peripheral portion, means for adjustably varying the position of the unit relative to the rotary member along a path that is substantially parallel to a radius of the rotary member, a first flexible connector secured at one end to the back-

40 ing member and at its other end to the unit, said flexible connector engaging said curved peripheral portion of the unit, and a second flexible connector secured at one end to the rotary member and adapted to be secured at its other end to a load, said second flexible connector

45 engaging said portion of the rotary member.

3. A device according to claim 2 including means for varying the effective length of the first flexible connector and the loading on the spring means.

4. A device according to claim 2 including means for limiting angular movement of the rotary member in either direction about the axis of the shaft.

5. A device of the character described comprising sup- port means including a housing having an end wall, a backing member within the housing, said backing mem- ber being spaced from and movable relative to the end wall, spring means within the housing, said spring means being positioned between and bearing against the end wall and the backing member, said spring means comprising a helical compression spring, a guide within the confines

60 of the compression spring, a shaft carried by the support means and disposed to the side of the end wall remote from the spring means, said shaft being substantially normal to the longitudinal axis of the compression spring, a rotary member mounted for rotation about the axis

65 of the shaft and having a peripheral portion which is a substantial part of an arc of a circle, a unit secured to and rotatable with the rotary member, said unit being so configured and arranged as to form a peripheral cam- ming surface, successive points along said camming sur- face lying on corresponding radii of the shaft which are of progressively increasing length, a first flexible connec- tor extending through the longitudinal opening defined by the compression spring and secured at one end to the backing member and at its other end to the unit, said

flexible connector engaging the guide and said curved peripheral portion of the unit, means for varying the effective length of the first flexible connector and the loading on the spring means, and a second flexible connector secured at one end to the rotary member and adapted to be secured at its other end to a load, said second flexible connector engaging said portion of the rotary member.

6. A device according to claim 5 including means for limiting angular movement of the rotary member in either direction about the axis of the shaft.
